UNITED STATES PATENT OFFICE.

GEORGE M. WILLIS, OF CHICAGO, ILLINOIS, ASSIGNOR OF ONE-HALF TO CHARLES A. BROWN, OF HINSDALE, ILLINOIS.

TRANSMISSION MECHANISM.

1,257,660.

Specification of Letters Patent. Patented Feb. 26, 1918.

Application filed June 12, 1914. Serial No. 844,605.

To all whom it may concern:

Be it known that I, GEORGE M. WILLIS, a citizen of the United States, residing at Chicago, in the county of Cook and State 5 of Illinois, have invented certain new and useful Improvements in Transmission Mechanism, of which the following is a full, clear, concise, and exact description, reference being had to the accompanying drawings, 10 forming a part of this specification.

This invention relates to engine starters.

In modern automobile construction it is common to employ a dynamo electric machine for starting the engine and for charging 15 the batteries when the engine is running.

Difficulty has been experienced in providing suitable transmission means between the starter and the engine. This transmission must fulfil the requirements of two classes 20 of service which are markedly different.

When the starter drives the engine a slow movement of great power is required as the engine is stiff and the periods of compression offer great resistance to turning of the 25 engine shaft. When the engine drives the starter a very rapid movement of greatly reduced power is required, but due to the two requirements it has become the practice among automobile engineers to employ two 30 separate units at an increased cost and an undesirable increase of weight and complicate mechanism.

It is desirable to use only a single unit and to employ a single transmission between the 35 engine and the starter. Heretofore, gears or chains and sprockets have been employed as they have been practically the only means for securing a positive driving action when starting; but these devices are objectionable 40 at the high engine speeds attained under ordinary operating conditions. Belts have been tried but are found to be unsuitable as they are too weak mechanically for the speed at starting, and if made sufficiently 45 strong and tight to act on starting duty, they cause friction and wear on the bearings when the engine is running at high speed.

The object of the present invention is to provide improved driving means between 50 the starter and the engine.

Another object is the provision of automatic means for increasing the adhesion of the driving belt to the transmitting wheels

when the starter is operating the engine and for decreasing the same when the engine 55 drives the starter.

A still further object is a provision of automatic means for tightening a power belt, which means will be brought into action automatically when the starter drives 60 the engine and which will be automatically dropped out of action when the engine drives the starter.

Accordingly, in my invention, a flexible chain belt is used as a transmission means 65 and automatic means is provided for increasing and relieving the tension in the belt at the proper times.

In the accompanying drawings—

Figure 1 is a view of an engine connected 70 to a starter employing a driving mechanism embodying the present invention showing the action which occurs when the starter is driving the engine;

Fig. 2 is a view of the same showing the 75 mechanism in the position assumed when the engine drives the starter;

Fig. 3 is a view of the type of grooved pulley employed on both the engine and the 80 starter shafts;

Fig. 4 is an end view of a link of the flexible chain belt;

Fig. 5 is a side view of the same;

Fig. 6 is a side view of a modification of 85 the tightening mechanism;

Figs. 7 and 9 are side views of other modifications;

Fig. 8 is a top view of the starter showing the attachment of the tensioning means.

In Fig. 1 the engine 1 is represented diagrammatically as connected by means of the belt 2 to the starter (not shown). A grooved pulley or sheave 3 is attached to the engine shaft and a similar but smaller sheave or pulley 4 is connected to the starter shaft 5. 90

Arms 8 and 9 support a pin 10 in proximity to the pulley 4 on the starter shaft. The arm 8 is rigidly fastened to the frame of the starter 7 to maintain the arms 8 and 9 in a fixed position. 95

The belt 2 (best shown in Figs. 3, 4 and 5) consists of a chain made up of bearing links 15 and connecting links 16. The bearing link has connected thereto a plate 17 secured by a saddle member 18 of tapered 105 configuration. An asbestos friction or bear-

ing pad 19 covers the sides of the saddle member 18 and presents a wearing surface of great resistivity to the tapered side of the groove in the pulleys. This bearing pad 19 5 may be constructed of leather, canvas, or the like, but is preferably constructed of an asbestos material to resist wear and heat. It is secured to the saddle member 18 by bent-over portions 20 of the saddle member 10 ber 18.

A T-shaped lever 22 bears the rollers 23 and 24 upon the arms 25 and 26. This lever is pivoted on the pin 10 and has a limited rotating movement on said pin. A pin 27 15 is arranged to come in contact with the links 8 and 9 to prevent the member 22 from dropping below a certain position as shown in Fig. 2.

The operation of the device is as follows: 20 When the starter is driving the engine as shown in Fig. 1, the parts will be rotated in a counter-clockwise direction and the lower span of the belt will be drawn taut between the pulleys 3 and 4. This action 25 tends to rotate the member 22 about the pin 10 as the lower span of the belt presses the roller 24 upward. The arm 25 is of greater length than the arm 26 and, as a consequence, the upper span of the belt 2 will be stretched by the raising of the member 30 22. This keeps both sides of the belt tight and draws the belt into the groove of the pulleys, the natural adhesion of the belt to the pulleys being insufficient to withstand 35 the great strain required to start the engine. As soon as the engine begins to operate, the starter will be driven by the engine and the upper span of the belt 2 will be drawn taut and the lower span will be slackened. 40 As this occurs, the member 22 rotates in a contra-clockwise direction about the pin 10, and, due to the greater amount of movement of the arm 25 over that of the arm 26 the pin 27 engages the shoulders on the 45 arms 8 and 9 and is held out of contact with both spans of the belt and no drag results as is customary in the usual belt tightening mechanism. This is especially 50 desirable as the engine operates at very high speeds and any amount of friction, however small, would materially reduce the efficiency of the transmission device.

In the modification shown in Fig. 6 the arms 8 and 9 are rotatable on the shaft 5 of 55 the starter and the lever 22 is normally held out of contact with the belt by means of the spring 30. This spring holds the arm against a pin 31 and thereby separates the electromagnet 32 which is connected to the 60 pin 10 by means of the rod 34 away from its armature 33. The electromagnet 32 is in series with the starting switch for closing the circuit of the starting motor 7 and as soon as the starter draws current to increase the tension on the lower span of the 65

belt the electromagnet 32 breaks the knuckle formed by the links 8 and 9 with the lever 22 and forces the lower roller 24 against the belt 2 causing the lever 22 to swing about this roller as a pivot and to force the upper roller against the belt as indicated in the dotted lines.

In the modification illustrated in Fig. 7 the arm 22, instead of bearing a roller at its upper end, is connected with a lever 35 75 pivoted at the point 36 and bearing at its outer end the roller 23. In this manner the upper span of the belt is pressed down when the starter is driving the engine and the lower span of the belt is drawn taut. The 80 operation of the structure shown in Fig. 7 is identical with that shown in Figs. 1 and 2 except that the lever 35 has been introduced to exert the pressure upon the belt from above to press the same inwardly instead of pressing the same outwardly.

The structure of Fig. 9 is similar to that of Fig. 6. Instead of operating the device by means of the electromagnet the arm 22 may be moved by means of an extension 90 of the starting switch shown as rod 37, to tighten the belt when the switch is closed.

It can be seen from the above that I have provided a transmitting means which automatically varies its action to suit the different classes of service to which it is subject. Under the driving action of the starter the belt is tightened and forced into the groove 21 of the pulleys. As soon as the engine operates to drive the starter tension on the 100 belt is automatically released, the rollers drop out of contact with the belt and no drag is exerted on the transmission means when the engine is running. It is obvious that a very great advantage and marked efficiency of transmission is secured thereby.

Although the invention has been illustrated with reference to the details of a particular embodiment it is not intended thereby to limit the invention except as limitations are embodied in the appended claims.

What I claim as new and desire to secure by Letters Patent of the United States is:

1. In an engine starting mechanism, an engine having a shaft, a starter having a 115 shaft, a pulley attached to the engine shaft, a pulley attached to the starter shaft, a belt connecting said pulleys and automatic means for tightening the belt when the starter drives the engine, and for releasing 120 the tension on the belt when the engine drives the starter.

2. In an engine starting mechanism an engine shaft, a starter shaft, a taper grooved pulley attached to the engine shaft, a taper 125 grooved pulley attached to the starter shaft, a tapered chain belt connecting said pulleys, the links of said chain bearing non-metallic friction means and automatic means for forcing the belt into the taper grooves when 130

the starter drives the engine and for releasing the tension on the belt when the engine drives the starter.

3. In an engine starting system, a starter shaft, a pulley upon said shaft, an engine shaft and a pulley mounted thereupon, a belt connecting said pulleys, a lever automatically operated when the starter drives the engine for tightening the belt between 10 said pulleys, said lever having operating arms of different lengths.

4. In an engine starting system, a starter shaft having a pulley thereupon, an engine shaft having a pulley mounted thereupon, a belt connecting said pulleys, a lever having arms of different length pivoted at one end to a fixed point and having a roller at one point adapted to bear against one span of said belt when the said span is under tension 20 and means connected to said lever for causing the other span of said belt to be tightened when the said first span is under tension from driving.

5. In an engine starting system, a starter shaft having a pulley thereupon, an engine shaft having a pulley mounted thereupon, a belt connecting said pulleys, a lever having arms of different length pivoted at one end to a fixed point and having a roller at one 30 point adapted to bear against one span of said belt when the said span is under tension and means connected to said lever for causing the other span of said belt to be tightened when the said first span is under 35 tension from driving, said lever mechanism being entirely free from said belt when the other span of said belt is under tension from driving by the engine.

6. In an engine starting system, a starter shaft having a pulley thereupon, an engine shaft having a pulley mounted thereupon, a belt connecting said pulleys, a lever having arms of different length pivoted at one end to a fixed point and having a roller at one 45 point adapted to bear against one span of said belt when the said span is under tension and means connected to said lever for causing the other span of said belt to be tightened when the said first span is under 50 tension from driving and a projection on said lever adapted to engage the fixed support when said other span is under tension from driving.

7. In an engine starting system, a starter

shaft, a pulley thereupon, an engine shaft, 55 a pulley mounted thereupon, both of said pulleys bearing tapered grooves, a tapered chain belt adapted to fit said grooves connecting said pulleys, a lever having arms of different length pivoted at one end to a fixed point and having a roller at one point bearing against one span of said belt when the said span is under tension, and means connected to said lever for causing the other span of said belt to be tightened when the 60 said first span is under tension from driving.

8. In an engine starting system, a starter shaft, a pulley thereupon, an engine shaft, a pulley mounted thereupon, a belt connecting said pulleys, a lever pivoted at one end to a fixed point, said lever bearing a roller at its outer end and a second roller intermediate the ends, said second roller engaging one span of the belt when the same is under tension from the starter driving the 75 engine, and thereby forcing said first roller against the loose span of the belt to tighten the same, said rollers being out of engagement with said belt when the engine drives the starter.

9. In a starting system, a starting shaft, bearing a pulley, an engine shaft bearing a pulley, a belt connecting said pulleys, a belt tightener having a roller bearing against the taut span of the belt when the starter 80 drives the engine, an arm connected to said roller and bearing a second roller for tightening the loose span of the belt, said belt tightener being inoperative when the engine drives the starter.

10. In a starting system, a starting shaft, bearing a pulley, an engine shaft bearing a pulley, a belt connecting said pulleys, a belt tightener having a roller bearing against the taut span of the belt when the 85 starter drives the engine, an arm connected to said roller and bearing a second roller for tightening the loose span of the belt, said rollers being out of contact with both spans of said belt when the engine drives the 90 starter.

In witness whereof, I hereunto subscribe my name this 28th day of May, A. D. 1914.

GEORGE M. WILLIS.
